UNITED STATES PATENT OFFICE.

HOWARD D. COLMAN, OF ROCKFORD, ILLINOIS, ASSIGNOR TO HOWARD D. COLMAN, LUTHER L. MILLER, AND HARRY A. SEVERSON, COPARTNERS DOING BUSINESS AS BARBER-COLMAN COMPANY, OF ROCKFORD, ILLINOIS.

TEXTILE-MACHINE.

1,149,499.

Specification of Letters Patent. Patented Aug. 10, 1915.

Application filed April 16, 1910. Serial No. 555,811.

To all whom it may concern:

Be it known that I, HOWARD D. COLMAN, a citizen of the United States, residing at Rockford, in the county of Winnebago and 5 State of Illinois, have invented certain new and useful Improvements in Textile-Machines, of which the following is a specification.

This invention relates to apparatus for operating upon warps, as, for example, for tying two warps together.

One of the objects of the invention is to arrange the apparatus so that while one piece of work (for instance, a pair of warps) 15 is being operated upon by the tying or other mechanism, the operator may be preparing another piece of work to be operated upon, whereby the mechanism may be kept in operation substantially all of the time and its 20 output made correspondingly large.

Another object of the invention is to provide power means for driving the mechanism of a textile machine which is movable into and out of operative relation to the apparatus that supports the various pieces of 25 work, and in which the mechanism is arranged to travel upon the bed of the machine.

The invention also relates to other features hereinafter described.

In the accompanying drawings, Figure 1 is a front elevation, somewhat shortened by breaking out portions, of an apparatus embodying the features of my invention. Fig. 35 2 is an end elevation of said apparatus. Fig. 3 is a sectional view taken in the plane of dotted line 3 3 of Fig. 1. Fig. 4 is a section on line 4 4 of Fig. 1. Fig. 5 is a fragmental top plan view of the apparatus. Fig. 40 6 is a section on line 6 6 of Fig. 1. Fig. 7 is a section on line 7 7 of Fig. 1. Fig. 8 is a front elevation of the lower part of the means for suspending a removable element 45 of the warp-tying machine. Fig. 9 is a section on line 9 9 of Fig. 8. Fig. 10 is a fragmental detail illustrating a different position of the parts shown in Fig. 9.

I will illustrate and describe my invention as embodied in warp-tying apparatus, without thereby intending to limit the invention to the tying of warps, since it is obvious that the principle of the invention is applicable to warp-drawing machines.

The embodiment herein illustrated by way

of example comprises a group or set of supports or frames 1 each adapted to support a pair of warps, and a warp-tying machine movable past said group of frames. The warp supports or frames may be generally similar to that illustrated in Patent No. 955,383, issued to me on April 19, 1910. Each of said supports, in the present instance, comprises two posts 2 for supporting a loom beam *a* having thereon a new warp, and arms 3 for supporting loom harnesses 65 operatively associated with a section of warp cut from a loom. Said section of warp will be hereinafter termed an old warp.

The warp-tying machine 4 may be generally similar to the one illustrated and described in British Patent No. 10,484 of 1905. The present form of said machine is mounted upon rollers 5 6 so that it may be traversed past the group or row of warp-supporting frames. If desired, some suitable 75 means may be used to hold the machine in adjusted position, as a brake 4^a. If desired, the warp-tying machine may be arranged to travel upon rails 7 8 laid upon the floor in front of the warp-supporting means. As 80 herein shown, the rail 8 is grooved and the rear rollers 6 have flanges thereon to travel in the groove of the rail. Upon the bed 9 of the warp-tying machine is a carriage 10 supporting a suitable mechanism for selecting threads from an old and a new warp 85 and for uniting such selected threads. This mechanism may be of any suitable character, as, for example, that fully illustrated and described in the before-mentioned British 90 patent. The driving connection between the carriage 10 and the bed or framework of the warp-tying machine may likewise be of any suitable nature, as, for instance, that disclosed in my said British patent. 95

The whole or a suitable portion of the new warp to be operated upon is supported upon the bed of the machine in any suitable manner, as, for instance, that illustrated in the said British patent, while the whole or a 100 suitable portion of the old warp is supported in a warp carriage 11, which may be similar to the one shown in the British patent before referred to.

For convenience in positioning the new 105 warp in the warp-tying machine, the warp carriage 11 is preferably made removable from its normal or operative position. I

have herein shown means for supporting the carriage so that it may be readily moved aside. I have also provided means for traversing the carriage 10 upon the bed 9 and 5 for actuating the mechanism on said carriage.

The warp-carriage-supporting means and the drive for the warp-tying machine are mounted upon a framework which may be 10 constructed as follows: Bars 12 and 13, which may be angle irons, fixed to and rising from each side of each warp-supporting means 1, are joined at their upper ends by horizontally extending bars 14. The forward ends of the bars 14 are secured to a bar 15 extending in front of and above the group of warp-supporting frames and running to a point at some distance beyond one 15 side of such group. If desired, a diagonal brace 16 may be arranged between the bar 15 and the rear portion of one of the bars 14. To the extended end of the bar 15 are fixed two brackets 17 and 18 spaced a suitable distance apart along said bar. In the outer 20 portions of said brackets is mounted a track 19 which, if desired, may be tubular, as shown in Fig. 6. As illustrated in said figure there is a slot in the lower side of the tube constituting the track, the surfaces at 25 opposite sides of the slot forming rails upon which rollers may run, as will appear hereinafter. The extended end of the bar 15 is supported, in this instance, by a tubular post 20 attached at its lower end to the floor in 30 any suitable manner. A track 21 which may, if desired, be similar to the track 19 is supported from the bar 15 by suitable means such as the bracket 18 and a sufficient number of brackets 22 23 24 25 26. The track 21 35 extends in front of and above the group of warp-supporting frames and to a point at a suitable distance from one side of said group, as indicated in Fig. 1.

In the present embodiment, power is communicated to the warp-tying machine by 40 means comprising a short shaft 27 carried by the bracket 26, said shaft having fixed upon one of its ends a grooved pulley 28 which receives a drive belt 29 extending over 45 a countershaft or other suitable source of power. On the opposite end of the shaft 27 is fixed a grooved pulley 30, and each of the brackets 23 and 25 has mounted thereon a 50 grooved idler pulley 31. The track 19 provides means for supporting one element of a suitable slack take-up for a belt 32 running over the pulleys 30 and 31 and suitable 55 pulleys on the warp-tying machine. In this instance the slack take-up comprises a carrier 33 provided with rollers 34 which run 60 within the track 19. On said carrier is a grooved pulley 35 for the belt 32. The carrier 33 is arranged to be moved along the track 19 in the direction to take up slack by 65 a suitable means, such as a weight 36 at-

tached to the carrier through the medium of a suitable flexible connection 37 extending over a guide sheave 38 near the upper end of the tubular post 20.

Fixed to the warp-tying machine is suitable means for guiding the driving belt 32 70 to the driven parts upon the machine. In this instance, said guide means comprises a bracket 39 fixed to the warp-tying machine, suitably braced and of such height as to support guide pulleys 40 at a suitable height above the floor so that the driving belt 32 may be out of the way of the operator. Upon a stationary part of the warp-tying machine are guide pulleys 41 for guiding the 75 belt 32 into operative relation with a pulley 42 upon the carriage 10. The shaft of the pulley 42 may be provided with a crank 43 for manually driving the mechanism and feeding the carriage.

The pulley 42 is preferably connected to its shaft by a suitable clutch arranged to be operated to disconnect the pulley from the shaft when the work in the machine has been completed or in case the thread-selecting 80 mechanism "stumbles."

One suitable form of such automatic throw-out is fully illustrated and described in my said British Patent No. 10,484 of 1905. The means for supporting the warp carriage 95 11 for convenient withdrawal consists, in this instance, of a carrier 44 provided with rollers arranged to travel within the track 21, said carrier having fixed thereto two vertical downwardly-extending rods 45. A 100 cross-bar 46 is fixed to these rods. The lower ends of the rods 45 are tubular to receive rods 47 fixed to brackets 48, a cross-bar 49 extending between said brackets.

To the lower side of each bracket 48 are 105 fixed two straps or loops 50 adapted to support rods 11^a forming part of the warp carriage 11. The devices 48 49 50 constitute a means for connecting the warp carriage to the rods 45. Said connecting means is vertically movable with relation to the rods 45, and is arranged to be moved by means herein shown as comprising a rock shaft 51 having crank arms 52 thereon, said crank arms being connected with the cross-bar 49 110 through the medium of links 53. The upper portions of said links are bent so that the point of pivotal connection between the links and the crank arms may be thrown over center to hold the warp carriage 11 in elevated position. The shaft 51 may be rocked by means of the hand lever 54 fixed upon one end thereof. 55 is a tension spring 115 extending between the rock shaft 51 and the cross-bar 49. When the hand lever 54 is 120 rocked to lower the warp carriage 11 and is thrown against the stop 56, the point of pivotal connection between the links 53 and the crank arms 52 is slightly over center, and the spring 55 holds the links and crank 125 130

arms in such relation, thereby locking the carriage-connecting means in its lowered position. When so lowered, the straps 50 are out of contact with the rods 11^a.

5 In use, a new warp and an old warp are placed in one of the warp-supporting frames 1, and the whole or a portion of the width of said warps is operatively placed in the warp-tying machine, said machine being positioned properly in front of said warp-supporting frame. The operator now pushes the carriage 10 forward until the mechanism on said carriage is in proper relation to the threads of the two warps. The operator 15 then clutches the pulley 42 to its shaft to permit the belt 32 to drive the warp-tying mechanism and feed the carriage 10. While the machine is operating upon the two warps as just described, the operator places another 20 pair of warps on the adjacent frame 1 and prepares said warps for reception in the warp-tying machine. When the warp threads contained in the warp-tying machine have been united, the mechanism is automatically stopped, as described in said 25 British Patent No. 10,484 of 1905. The operator thereupon removes the united warps from the machine and returns the carriage 10 to its initial position upon the 30 bed of the machine. The operator then moves the warp-tying machine along the front of the group of warp-supporting frames into position to operate upon another pair of warps or section of a pair of warps, 35 and places the warp-tying mechanism in operation, as before. When the carriage 10 advances upon the bed 9 the take-up 33 furnishes the necessary slack to the belt 32. When the warp-tying machine is advanced 40 along the front of the row of warp-supporting frames the belt automatically adjusts itself by running over the guide pulleys 40 41. When the warps upon one of the frames 1 have been united and the machine has 45 commenced to operate upon the warps in another frame 1, the united warps are removed from the first mentioned frame and a new set of warps placed therein and prepared for reception by the warp-tying machine. 50

It will be seen that the provision of a plurality of warp-supporting means permits the operator to prepare one piece of work for the machine while the latter is operating 55 upon another piece of work, thus permitting of a substantially continuous use of the machine.

When a new warp is to be placed in position in the warp-tying machine, the warp carriage 11 is elevated by rocking the shaft 51 into the position shown in Fig. 9, the carrier 44, with the warp carriage 11 suspended therefrom, being then pushed along the track 21 to a point at one side of the 60 warp-tying machine.

I would have it understood that the invention is not limited to the construction herein shown and described, for various modifications will occur to those skilled in the art.

70

I claim as my invention:

1. In a textile apparatus, in combination, means for supporting a plurality of pairs of warps side by side; a track extending in front of said supporting means; a warp 75 uniting machine movably mounted on said track, said machine comprising a bed, warp-holding means stationary with relation to the bed, a removable warp carriage, and a uniting mechanism arranged to travel upon 80 the bed in a direction parallel with the track; and an overhead carrier supported to move in a direction parallel with the track and connected to the warp-carriage.

2. In a textile apparatus, in combination, 85 a mechanism for operating upon a warp, a warp-supporting frame, a support above said mechanism, a part connected to said frame, a crank arm mounted on said support, a link connection between said part 90 and said crank arm, and means for swinging said crank arm to raise and lower the warp-supporting frame.

3. In a textile apparatus, in combination, 95 means for supporting two warps; a machine comprising a bed and a uniting mechanism which is movable upon said bed and transversely of the warps, said machine being movable as a whole past said warp-supporting means and transversely of the warps; stationary overhead supporting means arranged along the path of movement of said machine; a drive belt carried by said overhead supporting means; an upwardly extending bracket upon said machine; and guide pulleys on said bracket and upon the body of the machine for guiding the belt into operative relation with said mechanism. 100

4. In a textile apparatus, in combination, 110 a plurality of warp-supporting frames arranged side-by-side; bars rising from said frames; a horizontally-extending bar supported overhead by the first mentioned bars and extending transversely of and above 115 the front of said warp-supporting frames and extending to a point at one side of the group of warp-supporting frames; a support for said overhead bar at said point; a machine for operating upon the warps held 120 by said frames, said machine being movable as a whole transversely of and in front of said frames and parallel with said overhead bar; and a drive belt supported by said overhead bar and having an automatically adjustable connection with said machine.

5. In a textile apparatus, in combination, 125 means for supporting warp threads; a machine for operating upon said threads, said 130

machine comprising a plurality of clamps to hold a portion of the threads supported by said supporting means, said machine further comprising a mechanism which is movable transversely of the warp threads and with relation to the rest of the machine, and said machine being movable as a whole transversely of the warp threads; and a stationarily supported drive means having an automatically adjustable connection with said mechanism.

6. In a textile apparatus, in combination, means for supporting warp threads; a machine for operating upon said threads said machine comprising a plurality of clamps to hold a portion of the threads supported by said supporting means, said machine further comprising a mechanism which is movable transversely of the warp threads 15 and with relation to the rest of the machine, and said machine being movable as a whole transversely of the warp threads; a stationary support; and a drive belt carried by said stationary support and having an automatically adjustable connection with said mechanism.

7. In a textile apparatus, in combination, means for supporting warp threads; a machine for operating upon said threads, said machine comprising a plurality of clamps to hold a portion of the threads supported by said supporting means, said machine further comprising a mechanism which is movable transversely of the warp threads 20 and with relation to the rest of the machine, and said machine being movable as a whole transversely of the warp threads; a stationary support; a drive belt carried by said stationary support; means on said machine for guiding the belt into operative relation with said mechanism; and means for taking up slack in the belt.

8. In a textile apparatus, in combination, means for supporting warp threads; a machine for operating upon said threads, said machine comprising a plurality of clamps to hold a portion of the threads supported by said supporting means, said machine further comprising a mechanism which is movable 25 transversely of the warp threads and with relation to the rest of the machine, and said machine being movable as a whole transversely of the warp threads; a stationary support; a drive belt carried by said stationary support; an upwardly extending bracket upon said machine; guide means on said bracket and upon the body of the machine for guiding the belt into operative relation with said mechanism; and means for taking up slack in said belt.

9. In a textile machine, in combination, a pair of warp-supporting frames; a track extending transversely of and above said frames; a machine for operating upon the 30 warps and arranged for movement trans-

versely of and in front of said warp-supporting frames, said machine comprising a removable element; and a carrier supported by said track and connected to said removable element for removing said element from 70 said machine.

10. In a textile machine, in combination, a pair of warp-supporting frames; a track extending transversely of and above said frames; a machine for operating upon the 75 warps and arranged for movement transversely of and in front of said warp-supporting frames, said machine comprising a removable element; a carrier arranged to travel upon said track; and a connection 80 between said carrier and said removable element, said connection being operable to raise and lower said element.

11. In a textile apparatus, in combination, a plurality of warp-supporting frames arranged side by side; bars rising from said frames; a horizontally extending bar supported by the first mentioned bars and extending transversely of and above the front 85 of said warp-supporting frames; a mechanism for operating upon the warps held by said frames; and a drive belt supported by said horizontal elevated bar and having an automatically adjustable connection with 90 said mechanism.

12. In a textile apparatus, in combination, a plurality of warp-supporting frames arranged side by side; a machine for operating upon the warps and arranged for movement transversely of and in front of 100 said warp-supporting frames; said machine comprising a removable element; a horizontal support extending transversely of and above and in front of the warp-supporting frames; a track supported by and extending longitudinally of said support; a carrier arranged to travel upon said track and connected to said removable element for removing said element from said machine; and a drive belt carried by said elevated support and having an automatically adjustable connection with 105 said machine.

13. In a textile apparatus, in combination, a plurality of warp-supporting frames arranged side by side; bars rising from said frames; a horizontally-extending bar supported by the first mentioned bars and extending transversely of and above the front 115 of said warp-supporting frames and extending to a point at one side of the group of warp-supporting frames; a mechanism for operating upon the warps held by said frames, said mechanism being movable transversely of and in front of said frames; a drive belt supported by said horizontal 120 elevated bar and having an automatically adjustable connection with said mechanism; and a slack take-up for said belt arranged at the extended end of said horizontal elevated bar.

95

110

115

120

125

130

14. In a textile machine, in combination, a plurality of warp-supporting frames arranged side by side; bars rising from said frames; a horizontally-extending bar supported by the first mentioned bars and extending transversely of and above the front of said warp-supporting frames, said bar extending to a point at one side of the group of warp-supporting frames; a machine for 5 operating upon the warps and arranged for movement transversely of and in front of said warp-supporting frames, said machine comprising a removable element; a track extending longitudinally of said horizontal 10 elevated bar and above said frames; a carrier arranged to travel upon said track and connected with said removable element for removing said element from said machine; a drive belt carried by said horizontal ele- 15 vated bar; an upwardly-extending bracket upon said machine; guide means on said bracket and upon the body of the machine for guiding the belt into operative relation to said machine; and means at the extended 20 end of said horizontal elevated bar for automatically taking up slack in said belt.

15. In a textile apparatus, in combination, a mechanism for operating upon a warp; a warp-supporting frame; a support 30 for said frame; a bracket having a slidable connection with said support; means on said bracket for connecting the bracket to the warp-supporting frame; a crank arm mounted on said support; a link connection 35 between the bracket and said crank arm; and means for swinging said crank arm to raise and lower the warp supporting frame.

16. In a textile apparatus, in combination, a mechanism for operating upon a 40 warp; a warp-supporting frame; an overhead carrier; two rods extending downwardly from said carrier; two brackets each having a slidable connection with one of said rods; means on said brackets for loosely 45 engaging said warp-supporting frame; a rock shaft carried by said rods; a crank arm on said rock shaft having a link connection with said brackets; and means for rocking said shaft to raise and lower the warp 50 frame, said carrier being supported for

movement to convey the warp frame to a point at one side of said mechanism.

17. In a textile apparatus, in combination, a plurality of warp-supporting frames each adapted to support a pair of warps, 55 said frames being arranged side by side; a machine for operating upon the warps held by said frames, said machine being supported independently of said frames and being arranged to traverse the front of said frames; an overhead support extending along said frames; and a drive belt carried by said support and having an automatically adjustable connection with said machine. 60

18. In a textile apparatus, in combination, a row of warp-supporting frames arranged side by side; a machine comprising warp clamps and a mechanism for operating upon the warps held by said frames, 70 said machine being traversable in front of and beyond one end of said row of frames; an overhead support extending along said row of frames and from end to end of the path of traversing movement of said machine; and a drive belt carried by said support and having an automatically adjustable connection with said mechanism. 75

19. In a textile apparatus, in combination, a mechanism for operating upon a 80 warp, a warp-supporting frame, a supporting structure located above said mechanism, a part connected to the warp-supporting frame and guided by said support for vertical movement and means carried by said support for raising and lowering said part. 85

20. In a textile apparatus, in combination, a mechanism for operating upon a warp, a support located above said mechanism and comprising two vertically extending members, a part having a telescoping connection with said members, a warp-supporting frame loosely connected to said part, and means carried by said support for raising and lowering said part. 90
